METHOD OF MAKING SHEET METAL CAPS

Edward H. Johnson, Toledo, Ohio, assignor to
The Closure Service Company, a corporation of
Ohio

Application March 27, 1933, Serial No. 662,911

2 Claims. (Cl. 113—121)

My invention relates to a method of making caps of sheet material to be used as closures for bottles, jars or other containers.

An object of the invention is to provide a practical method of making a cap with double walls from a single piece of sheet metal. More particularly the invention comprises a novel method of stamping a disk from a sheet of metal and shaping the cap from said disk by a series of drawing operations performed in successive steps by means of dies.

Other objects of the invention and the exact nature thereof will appear more fully hereinafter.

In the accompanying drawings:

Fig. 1 is a diagrammatic view of a flat strip of sheet metal from which the blanks are stamped.

Fig. 2 is a sectional elevation of a cutter and dies by which a blank is stamped out and partially formed by a preliminary drawing operation which draws the inner flange portion of the cap.

Fig. 3 is a fragmentary view of the dies shown in Fig. 2 at the completion of the first drawing operation, and before the dies have been separated.

Fig. 4 is a sectional view of the blank as formed by the first drawing operation.

Fig. 5 is a view of the incomplete cap or blank shown in Fig. 4, but with the screw threads formed thereon.

Fig. 6 is a view showing a second set of dies for effecting an additional step in the drawing operation.

Fig. 7 is a similar view with the dies brought together.

Fig. 8 shows a pair of dies for effecting the final shaping operation.

Fig. 9 is a view of the same with the dies brought together.

Fig. 10 is a sectional view of the completed cap.

Referring to Fig. 1, circular disks or blanks 12 are stamped from a flat strip 13 of sheet metal which is fed between a pair of dies (Fig. 2). A stationary supporting platform or table 14 has mounted thereon a cutting ring 15 which cooperates with a cutter block or die 16 to sever the disk when said block is moved downward. Mounted on the platform 14 is a stationary lower die 17 which cooperates with an upper die 18 yieldingly mounted within the block 16 for relative up and down movement. Between the lower die 17 and the ring 15 is a supporting ring 19 which is normally held with its upper face in the same plane with the upper face of the die 17 and ring 15. The ring 19 is carried on posts 20 which extend downward therefrom through openings in the platform

14 and are attached to a yoke or disk 21 beneath the platform. A post 22 secured to the platform 14 and extending downward therefrom provides a support for a disk 23. A rubber block 24 mounted on the post 22 between the disks 21 and 23 5 provides a yielding support for the disk 21 and the ring 19 carried thereby.

In the operation of the dies shown in Fig. 2, after the sheet metal strip 13 has been fed forward into position between the dies, the upper 10 block 16 is moved downward and cooperates with the ring 15 to sever a circular blank or disk 12. As the block 16 continues its downward movement, the portion of the severed disk which extends beyond the top surface of the lower die 17, is 15 carried downward and shaped between the lower die and the upper dies 16 and 18, as shown in Fig. 3, in which the upper dies have completed their downward movement. The upper die 18 in cooperation with the lower die 17, draws a skirt 20 or flange portion 25 downward from the top portion 26 of the blank. When the die 18 has completed its downward movement, the outer die block 16 continues to move downward, thereby drawing and shaping a vertical flange portion 27 which 25 forms the lower part of the partially formed cap or blank. A coil spring 28 interposed between the inner and outer dies 18 and 16, holds the inner die normally in its lowered position relative to the outer die 16, so that said dies move downward 30 together during the first part of the drawing operation, and permits the outer die 16 to continue its downward movement after the die 18 has completed its downward movement. When the upper dies are lifted after the drawing operation, the 35 rubber block 24 which has been compressed by the lowering of the platform 19 returns the platform to its normal position.

The next step in the formation of the blank shown in Fig. 4 consists in rolling threads 29 40 (Fig. 5) in the flange portion 25. The threaded blank is now ready for the second drawing operation which is performed by means of the dies shown in Figs. 6 and 7. These include an annular die member 30 mounted on a platform 31, an inner die 32 yieldingly mounted for up and down movement in the die member 30, and an upper die 33. The upper portion of the die 33 is of somewhat reduced diameter to receive the blank which seats thereon, while the lower 50 flange portion 27 of the blank surrounds a reduced annular portion 34 of the die 30. The upper die 33 is of hollow cylindrical formation and is adapted to surround the flange portion 25 of the blank when moved downward. The die 55

33 carries a yielding head or plate 35 normally held in the lower end of the die by a coil spring 36. When the die 33 is moved downward, said head seats on the blank, and as the die continues its downward movement it is brought into position to surround the upper portion of the die 32 and the part 25 of the blank. A further downward movement of the upper die 33 carries the die 32 downward therewith, so that the die 33 enters the part 24 of the lower die 38, as shown in Fig. 7. The lower flange portion 27 of the blank is drawn upward by such movement of the dies to a vertical position between the die members 33 and 34. The blank is thus given the shape shown in Figs. 7 and 8 in which the outer portion 37 thereof forms the cylindrical outer wall of the cap.

The final shaping of the cap is effected by the dies shown in Figs. 8 and 9. These comprise a lower die 38 and an upper die 39. The die 39 is formed in its lower face with an annular recess 40 by which the upper marginal portion of the flange 37 is rolled inward and downward when the dies are brought together, thus forming a bead 41 which provides a marginal top surface surrounding the flat circular top 42 of the cap. Fig. 9 shows the upper die 39 in its lowered position with the cap in its finished form and held between the dies. Fig. 10 shows the cap after it is removed from the dies.

Modifications may be resorted to within the spirit and scope of my invention.

What I claim is:

1. The method of forming a cap from sheet material which comprises cutting a circular blank from a sheet of the material, drawing an intermediate portion of the blank downward substantially at right angles to a central circular portion of the blank to form an inner wall or skirt portion depending from said central portion, drawing the outer circumferential portion of the blank upward into approximate parallelism with said inner skirt portion, and rolling the free edge or margin of said outer portion inwardly and downwardly into the space between said inner and outer skirt portions and below the circular top portion. 15

2. The method which comprises drawing an intermediate annular portion of a sheet metal disk between dies to form a circumferential flange portion extending substantially at right angles to a circular central portion of the disk, rolling 20 screw threads on said flange portion, bending the peripheral portion of the disk back and drawing it into an outer cylindrical flange surrounding the screw threaded inner flange portion with the free edge of the outer flange portion protruding beyond the inner flange portion, and rolling 25 said free edge between said flange portions into position to form a beaded margin surrounding and in substantially the plane of the central circular portion of the cap. 30

EDWARD H. JOHNSON.
